Ludington & Ludlow.

Fertilizer.

No 12,508.

Patented Mar. 13, 1865.

UNITED STATES PATENT OFFICE.

H. LUDINGTON AND S. R. LUPTON, OF ADDISON, PENNSYLVANIA.

IMPROVEMENT IN LIME-SPREADERS.

Specification forming part of Letters Patent No. 12,508, dated March 13, 1855.

To all whom it may concern:

Be it known that we, H. LUDINGTON and S. R. LUPTON, of Addison, in the county of Somerset and State of Pennsylvania, have invented and made certain new and useful Improvements in Machines for Pulverizing and Spreading Lime and other Compost Matter; and we do hereby declare that the following is a full, clear, and exact description of the method of construction and mode of operating the same, reference being had to the accompanying drawings, and making a part of this specification, in which—

Figure 1 is a perspective view of the machine complete. A A are the running-gear wheels; B B, the body or box; C, the lime-chamber; D, the implement-chest; E E, the expanding sectional hopper; F F, the drum or cylinder; G, the fountain; H, the revolving spike-shaft; c c c c c c, the hinged-frame grating; d d e e, the gearing; f, the driving gear-wheels; g g, the ungearing device; h h, the adjusting or graduating screw; i i, cords to pull over the hinged-frame grating c c c c against the pulley-crane J J K K.

Fig. 2 is an inverted view of the bottom of the expanding sectional hopper, showing the compost-egress N M O.

Fig. 3 is a top view of the hinged expanding sectional hopper, showing the series of diagonal ridges or irregularities a a a a a and the crushing drum or cylinder, with series of ridges or irregularities p p p p p, and the longitudinal parallel gutters or troughs s s s s.

To enable others to be skilled in the use and application of our invention and improvements, we will proceed to describe the construction and operation thereof, the nature and principles of which consist in constructing a lime or compost spreader, Fig. 1, and arranging the same on an ordinary running-gear of two or more wheels, A A, Fig. 1.

This spreader is formed of a body or box, B B B, having a reservoir for lime, or a compost-chamber, C, and an implement-chest, D. We then have constructed a sectional expanding hopper, E E, hinged or hung on pivots by its upper edge, and having formed on its inner surface diagonal ridges or irregularities a a a a a, Fig. 3. We then have a cylinder or drum, F F, with a series of ridges or irregularities, p p p p, Fig. 3, formed diagonally across the periphery or circumference thereof. There are

also formed at intermediate distances between the ridges longitudinal and parallel troughs or gutters s s s s, Fig. 3.

With regard to the particular form of construction of the grinding-surface of the cylinder, Fig. 3, the following advantages and utility are embraced therein and a new result produced, viz: Because of the obliquely-arranged ridges or furrows p p p p emptying into the horizontally-formed gutters or troughs s s s s the pulverized particles do not escape and fall together in as great a volume or compact mass as they would if there were no such formation of gutters or longitudinal troughs s s s s, for it will be readily perceived that these troughs catch a portion of the pulverized mass and throw it out gradually as the cylinder revolves over, thus distributing or spreading with more regularity or equality than could be otherwise done with plain fluted cylinders, such as are used generally in compost spreading or distributing machines. This cylinder, Fig. 3, revolves within and parallel to the faces or inner surfaces of the expanding sectional hopper, Fig. 3. Now the advantage of this hopper is that, owing to its acting in combination with the cylinder, Fig. 3, an additional duty or function is embraced by regulating the coarseness or fineness of deposit, as well as of graduating or regulating the supply of deposit in increased or diminished quantities, aided by the spring b b b, Fig. 2, and screw h h, Fig. 1.

Next is formed an open-bottom detachable fountain, G, having arranged upon its top a hinged frame with a grating or succession of bent or curved rods or bars, as shown in Fig. 1 at c c c c c c. The utility of this grating is seen at once, for it is a well-known fact that in all compost or lime there are more or less of hard and lumpy portions, and therefore the lumps must be prevented from choking or falling onto and between the cylinder and expanding hopper, Fig. 3. The object therefore of this hinged grating c c c c c is to admit of the throwing off the lumpy portions, which is readily done by pulling the cords i i which pass over the pulleys J J of the cranes K K, through which the hinged grating c c c c c is tilted or thrown up and forward, the cranes K K, Fig. 1, answering as rests when the lumpy portions, rock and trash, are deposited on the ground, after which the hinged-frame grating can be thrown back in its place again.

Within the open-bottom fountain G and beneath the grating *c c c c* is arranged a horizontally revolving feeding and pulverizing spike-shaft, H. This shaft and the drum or cylinder F gear into each other by the wheels *d d e e*, and are driven by the driving-wheel *f*, Fig. 1. There is arranged on the side of the frame or box B B a gearing and ungearing device, *g g*.

The operation of our compost-spreader is as follows: A supply of compost is put into the reservoir or receptacle C and the fountain G is filled with lime or compost, and the machine being attached to one or more horses by shaft or tongue, the machine is set in motion, the gearing-wheels *d d e e* being put in action by the driving-wheel or motive-wheel A, and thus the cylinder F F and spike-shaft H are made to revolve, the compost or lime in pulverized form passing off through the bottom of the expanding sectional hopper and distributed over the soil.

Having thus fully described the construction and operation of our lime-spreader or compost machine, what we claim as of our invention, and desire to secure by Letters Patent of the United States, is as follows, viz:

1. The construction of an expanding sectional hopper, E E, Figs. 1 and 3, hung by hinges, or otherwise pendent, and formed with concaves on the inner sides, which concaves have formed thereon diagonally arranged ridges or sloping irregularities *a a a a a a a*, substantially as described.

2. The construction of a drum, cylinder, or

roller, F F, with series of ridges or sloping irregularities *p p p* formed or arranged diagonally across its circumference or periphery, together with longitudinal troughs or gutters *s s s s* at intervals between the ridges, as shown at Figs. 1 and 3, this cylinder being also combined in action or operation with the hopper E E, Fig. 1, and the revolving spike-shaft H, as set forth.

3. We are aware that there are such devices as tilting tables, dumping beds and cart-bodies and sloping or sliding planes for the purpose of precipitation. None of these, however, do we claim, as they are not equivalent forms of construction to ours, for they do not embrace the twofold principles of our device. Nor is it a fixed sieve or permanently-arranged grating that we claim; but instead we claim constructing a feeding or supply fountain having the combination of an adjustable hinged-frame grating actuated by cords or equivalents and to answer the twofold purpose of holding the compost mass and preventing the escape of lumps, &c., and admitting also of being elevated or depressed or thrown forward at pleasure for the purpose of relieving the grating and hopper or fountain of lumps and other obstructions, in the manner and for the purpose set forth.

H. LUDINGTON. [L. S.]
